UNITED STATES PATENT OFFICE.

ZEREE C. BRADFORD, OF DAYTON, OHIO, ASSIGNOR TO THE DAYTON ENGINEERING LABORATORIES COMPANY, OF DAYTON, OHIO, A CORPORATION OF OHIO.

ENGINE-STARTING APPARATUS.

Application filed May 15, 1925. Serial No. 30,519.

This invention relates to apparatus for starting internal combustion engines and, particularly, to improvements in the type of apparatus which comprises an electric motor, a gear operated by the motor and adapted to be moved into mesh with a gear connected with the engine to be started. The gear is connected with the electric motor by a mechanism which automatically completes the meshing of the gears by the rotation of the motor after the gears have once been brought into engagement, the connecting mechanism being arranged also to cause the motor operated gear to be moved out of mesh with the engine gear after the engine starts.

The objects of the invention include simplification of the construction of this type of starting apparatus in order to reduce the cost of manufacture.

Further objects of the present invention will be apparent from the following description, reference being made to the accompanying drawings:

Figs. 1, 2 and 3 are side views partially in section of starting apparatus embodying a form of the invention and showing the apparatus in different stages of operation;

Fig. 4 is a view looking in the direction of the arrow 4 in Fig. 1;

Fig. 5 is a side view of the pedal operated lever;

Fig. 6 is a side view of the pinion shifting fork;

Fig. 7 is a side view of the latch for engaging the pinion shifting fork and

Fig. 8 is a side view of one of the latch carrying members.

Referring to the drawings, the field frame of an electric motor is designated by numeral 20, and numerals 21 and 22 indicate the end frames which are secured to the field frame 20 by bolts 23 and nuts 24. Frames 21 and 22 provide bearings for supporting the motor armature shaft 25 which is provided with splines 26 which are oblique to the axis of the shaft 25. Shaft 25 is threaded at 27 to receive the nut 28 which serves as a stop for a gear 29 which is internally broached to receive the splines 26.

The hub of gear 29 is connected with a grooved collar 30 which is engaged by the ends 31 of a bifurcated shifting lever 32 which is pivotally supported by a bolt 33 attached to a bracket 34, integral with the end frame 21, by a nut 35. The bifurcations

of the lever 32 are joined together by a yoke portion 36 and a stud 37. The stud 37 operates with a latch plate 38 having a notch 39 for engaging the stud 37. Plate 38 is provided with a hole 40 for receiving a screw 41 which provides a pivotal connection between the plate 38 and two latch carrying levers 42 having holes 43 for receiving the screw 41 which is secured by a nut 44. The hole 45 in levers 42 receives the screw 33 which provides a pivotal support for the levers 42. Latch plate 38 carries a stud 46 which cooperates with a cam 47 formed integrally with the bracket 34.

Plate 38 is provided with a hole 48 for receiving a spring 49 which connects the plate 38 with an ear 50 provided by the pedal operated lever 51. Lever 51 is provided with a hole 52 for receiving screw 33 which provides a pivot for the lever 51. Relative motion between the lever 51 and the latch 38 is limited in one direction by the engagement of the screw 41 with a lug 53 provided by the lever 51. Lever 51 is provided with a hole 54 for receiving a pedal rod 55 which extends through the floor board 56 of an automobile and is provided, at its upper end with a pedal 57. A spring 58 located between the floor board 56 and the pedal 57 maintains the lever 51 normally in the position shown in Fig. 1.

The operation of the motor is controlled by a motor switch 60 comprising a switch case 61 which insulatingly supports a terminal screw 62, the head 63 of which bears against a leaf spring conductor 64 carrying a contact 65. Contact 65 is actuated by a non-conducting plunger 66 into engagement with contact 67 which is insulatingly supported by a motor field frame 20 and has its lower end 68 attached to one of the motor field windings not shown. As well known to those skilled in the art, the other end of the field circuit is connected with the insulated brush bearing against the motor commutator, and the brush of opposite polarity is grounded upon the motor frame. Upward movement of the plunger 66 is limited by the engagement with the switch case of a wire split ring 69 which is sprung into a groove provided by the plunger 66. The plunger 66 is located in the path of movement of an arm 59 carried by the lever 51.

The manner of operating the starter is as follows:

Normally the starter is in the position shown in Fig. 1. To start the engine the pedal 57 is pressed, causing the lever 51 to move clockwise. Motion from the lever 51 to the latch 38 is imparted through the spring 49. Until after the gear 29 is brought into mesh with the gear 70 of the engine to be started, the latch 38 remains in engagement with the stud 37. Therefore, clockwise movement of the lever 51 and latch 38 about the rod 33 will cause the gear 29 to move toward the left into engagement with the engine gear 70. If gear tooth abutment does not occur, the gear 29 will be moved manually into partial engagement with the gear 70. As the latch 38 moves upwardly, as viewed in Fig. 1, during the downward movement of the pedal 57, the stud 46 will be engaged by the cam 47. Since cam 47 is stationary, relative movement between the latch 38 and the latch carrying arms 42 will take place. Therefore the latch 38 will be moved out of engagement with the stud 37. This however will not occur until after meshing of the gears has begun.

As the lever 51 is pushed downwardly the arm 59 will engage the plunger 63 of the switch 60 and cause the motor circuit to be closed by the engagement of contacts 65 and 67. Then the motor will turn the shaft 25 and will thread the gear 29 into engagement with the stop 28 and into full enmeshment with the gear 70. Then the motor will crank the engine through the gears and, after the engine becomes self-operative, the gear 29 will be automatically demeshed from the gear 70 since the latch 38 is clear of the stud 37.

Fig. 2 shows the condition of the starting apparatus during the cranking of the engine. In this figure it will be seen that this latch 38 is clear of the stud 37 so that automatic demeshment may take place, when the engine becomes self-operative.

Fig. 3 shows the condition of the apparatus after the engine has become self-operative and before the operator has released the pedal 57. As the gear 29 is moved out of mesh automatically toward the right as viewed in Fig. 3, the grooved collar 30 will engage the lever 32 and cause it to move counterclockwise. This motion of lever 32 will cause the stud 37 to engage the latch 38 and cause the spring 39 to be stretched more than shown in Fig. 2 and will cause the stud 46 to be moved slightly away from the cam 47. In this way a yielding pressure is placed upon the stud 37 by the latch 38 producing a friction between these members tending to maintain the lever 32 in the position shown in Fig. 3.

In case of gear tooth abutment which limits the movement of the gear 29 toward the left (as viewed in the drawings) while the pedal is being depressed, the spring 49

permits the lever 51 to be moved downwardly to close the motor switch 60, in order that the shaft 25 may be turned to bring the teeth of the gear 29 into registry with the tooth spaces of the gear 70. When this occurs the spring 49 will be released in order to pull the gear 29 into mesh with the gear 70.

In case the engine should fail to start after gear meshing has been effected so that the gear 29 might remain in mesh with the gear 70, the mechanism is constructed so that the lever 51 may be released to open the motor switch although the gears 29 and 70 may remain in engagement as shown in Fig. 2. Although the lever 32 will remain in the position shown in Fig. 2 the parts 51, 38 and 42 may return to the position shown in Fig. 1 with the exception that the surface 38a of the lever 38 will rest upon the stud 37.

Heretofore, in starting devices of this type, three springs have been found necessary, namely: a spring corresponding to the pedal spring 58, a separate latch spring, and a separate spring for providing a yielding connection between the pedal and the pinion which will allow the motor switch to be closed in case of gear tooth abutment. By means of the present invention the number of springs has been reduced. The single spring 58 constitutes the yielding connection referred to and also the spring for yieldingly maintaining the latch 38 in engagement with a part of the gear shifting lever.

While the form of embodiment of the invention as herein disclosed, constitutes a preferred form, it is to be understood that other forms might be adopted, all coming within the scope of the claims which follow.

What is claimed is as follows:

1. An engine starter comprising, in combination, an electric motor, means for connecting the motor with the gear of an engine to be started and comprising a motor driven gear and provisions so constructed that operation of the motor completes engagement of the gears after meshing of the gears has been started and so that the gears will be demeshed automatically when the engine becomes self-operative, a pedal-operated member, a latch, a movable member movably carrying the latch, a part connected with the motor gear, a spring connecting the latch and pedal-operated member and normally maintaining the latch in operating connection with said part connected with the gear, a member engaged by the latch to disconnect the latter from said part after gear meshing has been started, and a switch operated by the pedal-operated member, said spring yielding in case of gear tooth abutment to permit closing of the switch before meshing gears.

2. An engine starter comprising, in com-

- 5 combination, an electric motor, a shaft having spiral splines operated by the motor, a gear adapted to mesh with an engine gear and slidably connected with said splines, a lever for moving the motor gear and moved by the motor gear, a pedal-operated member, a latch adapted normally to engage a part carried by the lever, a spring connecting the latch and pedal-operated member and urging the latch toward said part of the lever, a movable member movably carrying the latch, a stationary cam engaged by a part carried by the latch to disconnect the latch from the lever by movement of the pedal-operated member, and a motor switch operated by the pedal member, said spring yielding in case of gear tooth abutment to permit closing the switch before meshing gears.
- 10 3. An engine starter comprising, in combination, an electric motor, a shaft having spiral splines operated by the motor, a gear adapted to mesh with an engine gear and slidably connected with said splines, a pedal-operated lever, a latch-carrying lever, a lever for moving the motor gear and moved by the motor gear, all of said levers being coaxially mounted, a latch pivoted upon the latch carrying lever and adapted to be connected normally with a part carried by the gear-moving lever, a spring connecting the pedal-operated lever and the latch and tending to maintain the latch in engagement with said part of the latch, a cam engaged by a part of the latch during movement thereof to disengage the latch from the gear-moving lever, and a motor switch operated by the pedal member, said spring yielding in case of gear tooth abutment to permit closing the switch before meshing gears.
- 15 4. An engine starter comprising, in combination, an electric motor, a shaft having spiral splines operated by the motor, a gear adapted to mesh with an engine gear and slidably connected with said splines, a member for moving the gear and moved thereby, a latch for engaging a part of said member, manually operable means for moving the latch, a spring urging the latch toward said part, and a device engaged by the latch to disconnect the latter from the gear-moving member during the operation of said means, said latch having a portion which is located in the path of movement of said part of the gear-moving member while the manually-operated means is held in position for meshing gears, in order that, as the gear-moving member is actuated by the automatic demeshing motion of the gear, said part of the moving member will be engaged by the latch portion under spring pressure tending to prevent movement of the gear-moving member.
- 20 5. An engine starter comprising, in combination, an electric motor, a shaft having spiral splines operated by the motor, a gear adapted to mesh with an engine gear and slidably connected with said splines, a member for moving the gear and moved thereby, a latch for engaging a part of said member, manually operable means for moving the latch, a spring urging the latch toward said part, and a stationary cam engaged by the latch to disconnect the latter from the gear-moving member during the motion of said manual means into position to mesh the gears.
- 25 6. An engine starter comprising, in combination, an electric motor, a shaft having spiral splines operated by the motor, a gear adapted to mesh with an engine gear and slidably connected with said splines, a pedal-operated lever, a latch-carrying lever, a lever for moving the gear and moved by the gear, a bracket carried by the frame of the motor, a rod carried by the bracket and providing a bearing for all of said levers, a latch pivoted upon the latch-carrying lever and adapted to be connected normally with a part carried by the gear-moving lever, a spring connecting the pedal-operated lever and the latch and tending to maintain the latch in engagement with said part of the gear moving lever, a cam engaged by a part of the latch during movement thereof to disengage the latch from the gear-moving lever, and a motor switch carried by the motor frame and operated by the pedal member, said spring yielding in case of gear tooth abutment to permit closing the switch before meshing gears.
- 30 7. An engine starter comprising, in combination, an electric motor, means for connecting the motor with the gear of an engine to be started and comprising a motor driven gear and provisions so constructed that operation of the motor completes engagement of the gears after meshing of the gears has been started and so that the gears will be demeshed automatically when the engine becomes self-operative, a member for moving the gear and moved thereby, a latch for engaging a part of said member, manually operable means for moving the latch, a spring urging the latch toward said part, and a stationary cam engaged by the latch to disconnect the latter from the gear-moving member during the motion of said manual means into position to mesh the gears.
- 35 8. An engine starter comprising, in combination, an electric motor, means for connecting the motor with the gear of an engine to be started and comprising a motor driven gear and provisions so constructed that operation of the motor completes engagement of the gears after meshing of the gears has been started and so that the gears will be demeshed automatically when the engine becomes self-operative, a pedal operated member, a member movable with the

motor gear, a latch carried by one of the members and normally engageable with the other member for transmitting motion between the members, and a stationary abutment engaged by the latch during movement of the motor gear into mesh with the engine gear and operable to move the latch out of engagement with said other member.

9. An engine starter comprising, in combination, an electric motor, means for connecting the motor with the gear of an engine to be started and comprising a motor driven gear and provisions so constructed that operation of the motor completes engagement of the gears after meshing of the gears has been started and so that the gears will be demeshed automatically when the

engine becomes self-operative, a pedal operated member, a member movable with the motor gear, a latch carried by the pedal operated member and normally engageable with the gear-moving member for transmitting motion between the members, a device engaged by the latch during movement of the motor gear into mesh with the engine gear and operable to move the latch out of engagement with the gear-moving member, and a part carried by the gear-moving member and engageable with the latch when the pedal operated member is maintained in gear-meshing position.

In testimony whereof I hereto affix my signature.

ZERBE C. BRADFORD.
